CHAIN SOCKET WRENCH

Frank T. Danuskie, Pittsfield, Pa.

Application October 23, 1952, Serial No. 316,503

1 Claim. (Cl. 81—57)

This invention relates to wrenches adapted to be used in close quarters where it is difficult to turn a nut or bolt with a conventional wrench, and in particular a wrench having sockets journaled in opposite ends of a bar with an endless chain mounted on the bar and trained over the sockets at the ends whereby a socket at one end of the bar may be positioned over a nut or bolt and rotated by a crank on the socket at the opposite end of the bar.

The purpose of this invention is to provide means for turning a nut or bolt where it is difficult to place a conventional wrench over the nut or head of the bolt.

Various types of extensions have been provided for wrenches, however, in numerous instances it is necessary to provide a special tool for turning a nut or bolt in a comparatively inaccessible position on a motor vehicle engine or other machine. With this thought in mind this invention contemplates a wrench wherein a socket in one end that may be positioned over a nut or bolt head and that may be rotated from the opposite end of the wrench by an endless chain incorporated in the wrench.

The object of this invention is, therefore, to provide means for forming a wrench whereby a socket journaled in one end of a handle and positioned with the axis thereof perpendicular to the handle may be rotated by an endless chain from the opposite end of the handle.

Another object of the invention is to provide means for rotating a socket in one end of the handle of a wrench from the opposite end of the handle in which the socket may be held by a latch so that the device may be used as a conventional wrench.

A further object of the invention is to provide a wrench for turning nuts and bolts in close quarters in which the wrench is of a simple and economical construction.

With these and other objects and advantages in view the invention embodies an elongated bar having sockets extended therethrough and journaled in the ends, with an endless chain trained over said sockets and positioned to travel on the sides of the bar, and a crank having sockets therein to correspond with the sockets extended through the bar whereby the wrench may be actuated by the crank.

Other features and advantages of the invention will appear from the following description in connection with the drawing, wherein:

Figure 1 is a side elevational view illustrating the improved chain socket wrench showing a

2

crank extended from one end of the wrench and with part of the crank broken away.

Figure 2 is an elevational view looking toward one edge of the wrench.

5 Figure 3 is a longitudinal section through the wrench taken on line 3—3 of Figure 2, with part of the wrench broken away.

Figure 4 is a longitudinal section through the wrench taken on line 4—4 of Figure 1 and also 10 with part of the handle of the wrench broken away.

Figure 5 is a cross section through the bar or handle of the wrench taken on line 5—5 of Figure 4, showing a latch for holding a spring biased pawl of the wrench with the ratchet disengaged from a socket at one end of the wrench.

15 Figure 6 is a cross section through the handle of the wrench taken on line 6—6 of Figure 4 with the socket removed and showing the end 20 of one of the spring biased pawls of the wrench.

Figure 7 is an elevational view showing a crank 25 for operating the wrench, and with part of the crank broken away.

Referring now to the drawing wherein like reference characters denote corresponding parts the improved T-spot wrench of this invention includes a bar 10 providing a handle, sprockets 11 and 12 journaled in the ends of the bar, a chain 13 trained over the sprockets and positioned to slide over the edges of the bar, a square socket 14 extended through the sprocket 11 at 30 one end of the bar, a hexagonal socket 15 extended through the sprocket 12 at the opposite end of the bar, a spring biased pawl 16 for holding the sprocket 11 at one end of the handle, a spring biased pawl 17 for holding the sprocket 12 at the opposite end of the wrench and a lever 35 providing a crank 18 having a square opening 19 at one end for receiving the socket 14 and a hexagonally shaped opening 20 in the opposite end for receiving the socket 15.

The bar 10 forming a handle is provided with bifurcated ends providing flanges 21 and 22 at the end in which the socket 14 is positioned and flanges 23 and 24 at the end in which the socket 15 is positioned and, as illustrated in Figure 4 the sprocket 11 is journaled in annular recesses 25 and 26 in the flanges 21 and 22, respectively, and the sprocket 12 is journaled in similar annular recesses 27 and 28 in the flanges 23 and 24, respectively.

45 The socket 14 extends through, and is secured in the sprocket 11, preferably by welding and the socket 15, which extends through the sprocket 12, is secured in the sprocket by similar means.

In the design shown the chain 13 is formed with links and lugs and the sprockets are provided with spaced sockets or pockets 29 and 30, respectively, which receive the lugs, however, it will be understood that a chain of any suitable type may be used and the sprockets may be provided to correspond with the chain.

As illustrated in Figures 3 and 4 the spring biased pawl 16 is provided with a stem 31 that is slidably mounted in an opening 32 in the bar 10 and the spring biased pawl is resiliently urged toward the sprocket by a spring 33, one end of which bears against a shoulder 34 in the bar and the other against a collar 35 on the spring biased pawl. The end of the stem 31 of the spring biased pawl is provided with an arm 36 that is positioned to extend over a lug or finger 37 in an opening or cutout 38 for retaining the spring biased pawl with the end thereof withdrawn from the socket.

By this means the spring biased pawl 16 may be withdrawn to release the sprocket 11 when it is desired to turn the socket 14 with the chain and when it is desired to use the wrench as a conventional socket wrench the arm 36 is turned whereby it passes over the lug 37 and the spring 33 snaps the latch into the socket of the sprocket, as shown in Figures 3 and 4.

The spring biased pawl 17 at the opposite end of the wrench is formed in a similar manner wherein a spring 39 urges the spring biased pawl 17 into one of the sockets of the sprocket when an arm 40 on the end of a stem 41 of the spring biased pawl is turned so that it is free to pass over a lug 42 in an opening 43 into the handle or bar.

With the parts formed in this manner one of the sockets 14 or 15 may be placed over a nut or head of a bolt in a comparatively inaccessible location and with the spring biased pawls 16 and 17 released the socket at the opposite end of the wrench or handle is rotated by the crank 18 whereby a nut or bolt over which the socket is positioned may be tightened or removed.

The socket may be provided in different sizes and with the spring biased pawls released the device may be used as a conventional wrench.

What is claimed is:

In a chain socket wrench, a bar having bifurcated ends providing flanges, there being registering annular recesses in said flanges, a sprocket positioned between said pair of flanges and journaled in said recesses, a square socket member extending transversely through one of said sprockets and secured thereto, a hexagonal socket member extending transversely through the other sprocket and secured thereto, each of said sprockets being provided with a plurality of spaced radially extending pockets, a chain trained over said sprockets and having lugs engaging said pockets, a pair of pawls slidably mounted in said bar and mounted for movement into and out of engagement with the pockets in said sprockets, said pawls being arranged in end to end relation with respect to each other and each including a stem, there being an opening in said bar for slidably receiving said stem, said opening including an enlarged portion and a reduced diameter portion defining a shoulder therebetween, a coil spring composed on said stem and abutting said shoulder for urging said pawl into engagement with a pocket, a collar mounted on each pawl adjacent a sprocket, said coil spring being positioned in the enlarged portion of said opening and abutting said collar, there being a pair of cutouts in said bar for receiving the inner ends of said pawls, a finger positioned in each cutout, and an arm secured to the inner end of said pawl for engagement with said finger.

FRANK T. DANUSKIE.
